UNITED STATES PATENT OFFICE.

ARCHER LE ROY BOLTON, OF NORTH ANDOVER, MASSACHUSETTS.

BUILT-UP MEMBER FOR PAPER-PULP ENGINES.

Application filed November 21, 1923. Serial No. 676,034.

To all whom it may concern:

Be it known that I, ARCHER LE ROY BOLTON, a citizen of the United States, residing at North Andover, in the county of 5 Essex and State of Massachusetts, have invented certain new and useful Improvements in Built-up Members for Paper-Pulp Engines, of which the following is a specification.

10 This invention relates to paper manufacturing, and has to do particularly with pulp engines such as are known as beaters, and such as are known as Jordan engines.

In what are known as beater engines 15 there is a cylindrical beater roll from the curved surface of which project bars or blades which serve to operate on the paper stock in a relatively slow manner, while in Jordan engines, there is a casing of truncated conical form from which project knives, and inside of which revolves a plug having bars on its outer surface, such plug revolving at a very high rate of speed.

It would be possible to make beater rolls 20 and also Jordan shells and plugs of solid metal, but for many reasons this is objectionable.

It has been found more satisfactory in the trade to fasten the bars, blades or knives 25 at intervals, to the metal body and to drive in between them wooden members which hold them in place in a more or less elastic manner, and in such a way that there is no rattle nor vibration.

30 A beater roll operates relatively slowly on unconfined stock and the wear on the blades and woods is not very great, but in the Jordan engine, the stock is confined and operated on at a high rate of speed, with 35 the result that the exposed face of the wood becomes worn and weakened.

When these wooden supports become 40 weakened on their faces, if the blades, bars or knives, encounter any hard substance the weakened wood on the face is crushed and the metal displaced so that repairs are necessary.

In an application now pending, Serial 45 Number 609,409 of Dec. 28, 1922, "Covering for plug of Jordan engines," I have 50 described the uses of protecting metal strips positioned on the face of the wooden supports or woods in a Jordan plug, but in this application I intend to cover similar

strips or truss plates applied to a Jordan shell as well as a plug, and also to a beater roll.

All three have a metal body of circular cross sections the centres of which form a straight axial line, and all have metal bars which may be called blades, bars or knives, each of which if straight, is disposed in a plane which passes through the axial line, or if curved or bent is radially disposed edgewise with reference to said axial line.

With the plug and roll and in some types of shells, these bars are fastened at one edge to the metal body, and in all cases I use wooden supports between the adjoining metal bars together with metal truss plates positioned substantially parallel or concentric to the face of the metal body, which truss plates rest on the wooden supports and are fastened between adjoining bars medially between their opposite edges.

These truss plates protect the woods from 55 wear and disintegration, and also greatly strengthen the construction because they support the bars near the middle line of their width while in the old construction where the bars fit in grooves, the leverage 60 on a groove is tremendous, if the face of the woods is worn away or is not strong enough to resist the pressure.

It is not necessary however, that my truss plates should fit with machined accuracy 65 between the bars, as a slight yielding is not objectionable, and in fact may be an advantage in taking up shocks.

In all these devices, the woods or wooden supports are preferably when dry, forced 70 or driven in between the bars. When they swell, the woods hold the bars firmly in position and help to take up any vibration which occurs. The wooden supports therefore, serve as cushions.

By using my truss plates on top of the woods I have a middle line of support on each side of each bar and in most constructions another line of support at the bottom. This bottom line of support may be grooves, 75 welding or supplementary bottom truss plates.

My truss plates may be used with a Jordan plug having a continuous conical body, a skeleton body made up of a series of 80 spiders, a removable, built-up jacket for 85

Jordan engine plugs such as shown in my application Serial No. 617,811 filed Feb. 8, 1923 pending herewith, or a removable lining shell for Jordan engines such as shown 5 in my application filed June 29, 1922, Serial Number 571,720 both pending herewith.

In fact it may be used with any type of Jordan plug or shell or with any type of beater roll.

10 In the drawings, Fig. 1 is a side elevation of the plug for a Jordan engine, removed therefrom and equipped with my device.

Fig. 2 is a fragmentary enlarged section, 15 as on the line 2—2 of Fig. 1.

Fig. 3 is a detail sectional side elevation showing part of a plug body formed of a series of spiders instead of a continuous body.

20 Fig. 4 is a sectional view similar to Fig. 2, showing the application of my device to another type of bodily removable covering.

Fig. 5 is a sectional view showing part of a Jordan shell with a removable lining with 25 my device applied thereto.

Fig. 6 is a sectional elevation showing the inside of a Jordan shell with a few knives and woods in place.

Fig. 7 is a sectional elevation enlarged on 30 line 7—7 of Fig. 6.

Fig. 8 is a sectional elevation of another modification of a Jordan shell.

Fig. 9 is a longitudinal sectional elevation showing a modified form of truss plate 35 which might be used with a Jordan plug or shell or with a beater roll.

Fig. 10 is an elevation of a beater roll built up of spiders with some of the bars, woods and my truss plates in position.

40 Fig. 11 is a detail from the right of Fig. 10.

Fig. 12 and Fig. 13 are details of beater bars in position.

Fig. 14 is a sectional detail showing a 45 modified type of truss plate applied to a beater roll.

Fig. 15 is a perspective view showing how my truss plates may be modified in configuration.

50 Figs. 16 and 17 show end views of different forms.

Figs. 18 and 19 show side elevations of different forms of truss plates.

In the drawings, A represents the shaft of 55 a Jordan engine plug B which has a large head 11 where the ring 7 is shrunk on, and a small head 10 where the ring 6 is shrunk on, with a hollow truncated conical body 20 between them.

60 Running longitudinally of shell 20 are the exterior longitudinal slots 21 and 22 in which are located the long bars C and the short or intermediate bars D in adjacent slots. The long bars C are shown as located in slots 21 and the short bars D in slots 22. The short

bars extend from the large end out half-way or part of the length of the shell.

As is customary in these plugs there are annular bosses extending around the body, each of which is cut away to allow a holding ring such as F to be shrunk in place with room underneath to receive a tongue of a bar C or D. The bars C and D are thus held from working radially outward in a well-known manner.

70 30, 30 represent the woods which are of wedge and key shape of a well-known type, forced in radially between the short bars D, and 31 represents similar woods forced in between the long bars C, C up to the inner 75 end of the bars D.

Near the inner end, the woods 30 are recessed or notched at 32 to a depth equal to the thickness of the metal strips H and the surface of the woods 31 is at the same height as 32 so that the strips H can rest flat and smoothly on them, with their top faces level with the top faces of woods 30.

80 I prefer to have the woods 30 extend down to the inner ends of short bars D, and to have the metal strips H slotted at 63 to pass beyond the inner end of a short bar D as thereby the inner end 40 of each bar, which is generally a weak spot, is supported more 85 rigidly.

85 Strips H are shown as having at the small end holes 61 for machine screws such as 71 which pass through them and through the woods into the body 20.

90 They are also shown as having such screw holes 61 for similar screws 71 at their inner end. Intermediate with these ends are the holes 62, 62 through which wood screws 70 may be passed into the woods 31 or into the 95 woods 30.

95 As the greatest strain and wear comes on the small end, I find that if any machine screws are desirable they may be located at this end. If desired, others at the inner end 100 may be located, or in many cases wood screws alone, which do not enter the metal, 105 are all that is necessary.

110 My strips being located between the bars at a point well up from their bases and extending around the plug in annular form, 115 not only protect the wood underneath from the wear and action of the stock but hold the bars much more firmly in position.

120 However, while it is desirable that the woods should be forced into position and should swell so as to hold the bars firmly and help take up the vibration, it is not necessary that my metal strips should fit with an accurate drive fit.

125 As shown at Y, Y, Fig. 2, if there is a slight space between the strip and the bars, it is impossible for the bar to tip over more than a very slight extent before it is stopped and held by the strip.

130 The dotted line X in Fig. 2 shows the

usual manner in which the woods wear down on one side, thus leaving the bar unprotected and unsupported on that side.

If the bar is held merely at its base in a groove 21 or 22, it will break or tip over, but with my metal strips extending around the plug between bars, no one bar can fall over.

It is obvious that my supporting and protecting strips might be cut in various other ways to protect the woods only or, preferably, to protect the woods and also laterally brace the bars at a line relatively high up from their bases.

15 In Fig. 3, I show a construction of plug wherein the body, instead of being a continuous member, such as shown at 20, with continuous longitudinal grooves, consists of a series of spiders, such as 80, 80, of varying 20 diameters, in the outer rims of which are bar slots, such as 81, so aligned as to receive the bars C or D, as the case may be.

25 In Fig. 4, I show another type of removable covering, 90 represents a continuous conical plug body of the same type as 20, and upon this is placed a thin sheet metal shell 91 of conical shape upon which are built up the bars C, woods 31 and protecting strips H.

30 These strips are attached to the woods as by screws 70, and the whole structure may be attached to the permanent body 90 by means of machine screws 71.

35 Instead of slots, the bottom edges of the bars may be spot-welded at 92 to the sheet metal shell 91, thereby supporting the bases, while the strips H form a second line of metallic support medially between the top and bottom of each bar. The whole built-up 40 jacket can be removed at will.

45 In the claims, when I refer to "means to hold the bars in place from radial and longitudinal displacement," I refer to the slots or spot-welding for the first and the usual rings 10 and 11 or their equivalent for the second.

50 It will be understood that the truncated conical body, with which my device may be used, may be a continuous hollow shell carried by large and small heads, a series of spiders of varying diameters, or a removable covering for either of such bodies, or any other similar foundation.

55 In Fig. 5, 50 represents the fixed casting of a Jordan shell and K represents a thin metal lining such as described in my pending application, Serial No. 571,720 mentioned hereinbefore.

60 In this construction, the knives 51 are spot-welded at 4 to shell K and are separated by woods 52. Truss plates 53 and 54 are fastened to the woods by screws 55.

65 At 57 I show a truss plate the end 56 of which is bent over to cover the end of the wood and is preferably held thereto by an additional screw 58.

In Fig. 5 the shell K may be regarded as the metal body.

In Figs. 6 and 7 I show a continuous shell body L in which longitudinally are fixed lugs 47 between which are driven the knives 70 51 and woods 52 on top of which are the truss plates 53 and 54.

As shown, the lugs 47 are fastened to L by screws 150 and on top of them are the thin woods 151.

In Fig. 8, I show the shell such as L inside of which are built up the knives 102 between which are the woods 103. In this case I use top truss plates 106 and bottom truss plates 101 fastened to the woods by 80 screws 104 and 105.

In Fig. 9, M represents the permanent body of any of the three machines and K is a thin metal body fixed thereto.

51 represents a bar, blade or knife and 52 85 a wooden support while the truss plate 57 is bent at each end 56 and is fastened to the woods by screws 55, 58 and 59.

Fig. 10 shows a beater roll of the usual skeleton construction comprising spiders N 90 mounted on a shaft S. These spiders have slots 74 which are properly aligned, those in the intermediate spiders 73-73 extending across and those in the end spiders 72 extending part way in.

The bars 75 fit into these slots and are separated by woods 78 upon the outer faces of which I locate my truss plates 76. These are fastened to the woods by means of screws 79.

In such beater rolls, the bars 75 are slotted at each end 84 and in each slot is located a ring 83 which holds them from radial displacement.

Another advantage of my truss plates is 105 that where only wood is used and the bars are tipped, as shown by the dotted lines in Fig. 13, the ring 83 is bent and broken. My truss plates prevent this.

As shown in Fig. 14 my truss plate 95 may 110 be bent over at 96 and fastened to the wood 78 by screws 97 thereby preventing the holding ring 83 from slipping out of the bar slot or notch 84.

As shown in Fig. 15 my truss plate, especially for beater rolls, may be thick at one part 86 and thin at another part 87 or it may be narrowed in at another part such as 88 or in fact may be made of any suitable shape to conform to the requirements of 120 strength, etc.

It may have an end section such as 98 in Fig. 16 or 99 in Fig. 17, or the edges 111 and 112 may be slotted as shown in Fig. 18 or otherwise reduced as shown at 113 and 114 in Fig. 19 so that if it is necessary to fit them between the bars the labor of grinding down will be reduced.

In the claims, when I speak of bars, I include knives and blades of all kinds and 130

when I speak of wooden supports, I include woods, wedges and all kinds of separators.

I claim:

1. The combination in a built up member for paper pulp engines of a metal body having circular cross sections, the centres of such sections forming a straight axial line, with metal bars each of which is disposed in a plane which passes through the axial line and is fastened at one edge to the metal body, wooden supports between adjoining bars and said body, and metal truss plates positioned substantially concentric to the surface of the body which rest on the faces of, and are fastened to the wooden supports between adjoining bars medially between their opposite longitudinal edges. 55
2. The combination in a built up member for paper pulp engines of a metal body having circular cross sections, the centres of such sections forming a straight axial line, with metal bars each of which is disposed in a plane which passes through the axial line and is fastened at one edge to the metal body, wooden supports between adjoining bars and said body, and metal truss plates positioned substantially concentric to the surface of the body which rest on the faces of the wooden supports and are fastened between adjoining bars medially between their opposite longitudinal edges. 60
3. The combination in a built up member for paper pulp engines of a metal body having circular cross sections, the centres of such sections forming a straight axial line, with metal bars each of which is disposed in a plane which passes through the axial line, wooden supports between adjoining bars and said body, and metal truss plates positioned substantially concentric to the surface of the body and fastened between adjoining bars medially between their opposite longitudinal edges. 65
4. The combination in a built up member for paper pulp engines of a metal body having circular cross sections, the centres of such sections forming a straight axial line, with metal bars radially disposed edge-wise with reference to said axial line, wooden supports between adjoining bars and said body, and metal truss plates positioned substantially concentric to the surface of the body and fastened between adjoining bars medially between their opposite longitudinal edges. 70
5. The combination in a built up shell for Jordan engines of a truncated conical metal body, with metal bars each of which is radially disposed edge-wise with reference to the axis thereof and has one edge resting on said body, means to prevent displacement of said edge with reference to said body, wooden wedges between adjoining bars and said body, and metal truss plates positioned substantially concentric to the surface of the body which rest on the faces of, and are fastened between adjoining bars medially between their opposite longitudinal edges. 75
6. The combination in a built up member for paper pulp engines of a metal body having circular cross sections, the centres of such sections forming a straight axial line, with bars arranged longitudinally along said body, means to hold the bottoms of said bars in place thereon, wooden supports between adjoining bars, and a series of protecting metal truss plates extending on top of some of the wooden supports and between the bars entirely around one part of the body. 80
7. The combination in a built up member for paper pulp engines of a body with longitudinal slots, with bars located in said slots, woods resting on the body between adjoining bars, a series of truss plates extending on top of the woods and between the bars, and means to hold the bars in place from radial and longitudinal displacement. 85
8. A protecting metal truss plate for the wooden supports of paper pulp engines having screw holes to receive fastening screws. 90

ARCHER LE ROY BOLTON.
